CLAIM

The ornamental design for a multi-compartment jewelry box, as shown and described.

DESCRIPTION

FIG. 1. is a perspective view of my multi-compartment jewelry box;

FIG. 2. is a view similar to FIG. 1, but showing the compartments in the closed position;

FIG. 3. is a front view of my design as depicted in FIG. 2;

FIG. 4. is a back view thereof;

FIG. 5. is a left side elevational view thereof with the right side being a mirror image thereof;

FIG. 6. is a bottom view thereof; and,

FIG. 7. is a top view thereof.
